(57) **ABSTRACT**

A new and distinct variety of grapevine characterized by the production of medium to large, red-colored seedless grapes that mature in late September, approximately nine weeks later than 'Flame Seedless' (unpatented) when grown in the San Joaquin Valley of Central California. The grapes of this new variety are produced on strong woody stems and branches and are well adapted to commercial handling.

1 Drawing Sheet

1

Latin name of the genus and species of the plant claimed: The claimed plant relates to a new and distinct variety of *Vitis vinifera* to be known as 'Sheegene-20'.

Variety denomination: The new variety of *Vitis vinifera* is the result of hybridization of 'Princess' (unpatented), the pollen parent, and 'Red Globe' (U.S. Plant Pat. No. 4,787), the seed parent. The new variety was first hybridized by Timothy P. Sheehan in the spring of 2000. The new variety was asexually propagated in the dormant season of 2003, grafted on one hundred seventy-two vines of 'Freedom' virus-free grape rootstock near Fresno, Calif. The new variety was planted in a *Vitis vinifera* variety block located near Fresno, Calif., on the north side of Muscat Avenue approximately five miles east of State Route 145. The new variety produces a medium-large, red-colored seedless grape with good flavor. The new variety has been shown to maintain its distinguishing characteristics through asexual propagation.

CROSS REFERENCE TO RELATED APPLICATIONS

The claimed plant is not subject of a related application.

STATEMENT OF ANY FEDERALLY-SPONSORED RESEARCH AND DEVELOPMENT

The claimed plant is not subject of Federally-sponsored research or development.

BACKGROUND OF THE INVENTION

The present invention relates to a new and distinct variety of grapevine that produces a medium-large, red-colored seedless grape that matures during late September when grown in the San Joaquin Valley of Central California. The new invention resembles 'Flame Seedless' (unpatented).

SUMMARY OF THE INVENTION

The 'Sheegene-20' grapevine is characterized by producing a medium-large, red-colored seedless grape that good

flavor and it is productive and mature for harvesting and shipment in late September when grown in the San Joaquin Valley of Central California. The new variety can be compared to 'Flame Seedless' (unpatented) but the grapes produced by the new variety mature approximately nine weeks later, among other distinguishing characteristics.

BRIEF DESCRIPTION OF THE DRAWINGS

10 The accompanying drawing is a color photograph that displays leaves along the left side, leaves with tendrils along the right side, clusters of the immature and mature grapes in the center, and on the bottom two grapes cut in half displaying the color of the flesh and the shape of the berries.

15 **DETAILED BOTANICAL DESCRIPTION**

Referring more to the horticultural description of the new and distinct variety of grapevine, the following has been 20 observed under the ecological conditions prevailing at the origin vineyard located near Fresno, Calif., in the San Joaquin Valley of Central California. All major color descriptions are by reference to the Dictionary of Color by Maerz & Paul, First Edition, published in 1930. Common colors names are also 25 used in several instances.

Vine:

Size.—Medium to large for two-year old vine.

Vigor.—Very good.

Chilling requirements.—Normal for grapevines in the San Joaquin Valley of Central California.

Figure.—Wide cordons forming a "T" shape figure.

Production capacity.—Very good.

Regularity of bearing.—Regular.

Trunk:

Size.—Medium to large; 4½ inches [11.43 cm] in circumference, 15 inches [38.10 cm] above graft.

Surface texture.—Rough, shaggy.

Color of bark.—Pl.7 H10 Piccadilly, Mauvewood +.

Mature cane color.—Pl.7 H9 Liver Brown and Autumn Oak.

<i>Nodes.</i> —Three nodes on canes.		<i>Size.</i> —0.16 inches [4 mm].
<i>Length between nodes.</i> —3 to 4 inches [7.62 to 10.16 cm].		<i>Petals (color).</i> —Pl.18 J7 Spring gr.
<i>Lenticel numbers.</i> —None.		<i>Petals (size).</i> —Small; 0.08 inches [2 mm].
<i>Shoot length.</i> —17 to 32 inches [43.18 to 81.28 cm].	5	<i>Pistil color.</i> —Pl.17 L8 Neva gr.
<i>Shoot shape.</i> —Contour drooping.		<i>Date of visible berry set.</i> —May 12, 2010.
<i>Tendrils numbers.</i> —Single at nodes.		<i>Size of berries.</i> —Small; 0.08 inches [2 mm].
<i>Tendrils size.</i> —Large; 5½ to 8¼ inches [13.97 to 20.96 cm].		Fruit:
<i>Tendrils form.</i> —Bifurcate.	10	<i>Solids.</i> —19.2 Brix.
<i>Tendrils texture.</i> —Firm.		<i>Acids.</i> —0.45.
<i>Bud shape.</i> —Triangular.		<i>Sugar/acid ratio.</i> —42.6.
<i>Bud size.</i> —0.02 inches [6 mm] in width, 0.03 inches [8 mm] in length.	15	<i>Juice pH.</i> —3.32.
Branches:		<i>Seeds.</i> —None.
<i>Size.</i> —Medium to large; 6 inches [15.24 cm] in circumference.		<i>Capstem pedicel.</i> —0.24 to 0.35 inches [6 to 9 mm].
<i>Cordons.</i> —32 to 35 inches from trunk (81.28 to 88.90 cm).	20	<i>Berry weight.</i> —11.36 grams.
<i>Surface texture.</i> —Slightly rough with groove.		<i>Juice color.</i> —Pl.13 L4 Near Bistre gr.
<i>Color (one year or older wood).</i> —Pl.7 H9 Liver Brown+Autumn Oak.	25	<i>Cluster size.</i> —Medium to large.
<i>Color (immature branches).</i> —Pl.19 K6 Sea gr. on lower side of branch; Pl.52 L8 Cineraria on upper side of branch.		<i>Cluster average length (not including stem).</i> —7.31 inches [18.57 cm].
Leaves:		<i>Cluster average diameter.</i> —4.82 inches [12.24 cm].
<i>Size.</i> —Medium to large.		<i>Cluster average weight.</i> —1 lbs. 2 oz. [511.2 grams].
<i>Density.</i> —Dense.		<i>Compactness.</i> —Compact.
<i>Average length.</i> —4.72 inches [11.99 cm].	30	<i>Cluster form.</i> —Conical.
<i>Average width.</i> —6.89 to 7.09 inches [17.50 to 18.01 cm].		<i>Stem (generally).</i> —2.17 inches [5.51 cm].
<i>Form.</i> —Pentagonal.		<i>Stem (caliper).</i> —0.16 to 0.24 inches [4 to 6 mm].
<i>Texture (upper surface).</i> —Smooth.		<i>Berry size.</i> —Medium to large.
<i>Texture (lower surface).</i> —Slightly glabrous.	35	<i>Berry form.</i> —Ovate.
<i>Color (upward disposed surface).</i> —Pl.23 J9 Mt. Vernon gr.		<i>Berry numbers.</i> —45 to 75 berries per bunch.
<i>Color (downward disposed surface).</i> —Pl.21 L7 Med. Dark gr.		<i>Berry size (average dimension along longitudinal axis).</i> —0.98 to 1.26 inches [2.49 to 3.20 cm].
<i>Leaf vein color.</i> —Pl.17 L7 Viridine Y.	40	<i>Berry size (average dimension along transverse axis).</i> —0.79 to 0.87 inches [20 to 22 mm].
<i>Marginal form.</i> —Slightly undulated.		Skin:
<i>Leaf vein thickness.</i> —0.008 inches [2 mm].		<i>Skin thickness.</i> —Medium.
<i>Leaf margin.</i> —Toothed.		<i>Texture.</i> —Tough.
<i>Glandular characteristics.</i> —None.		<i>Tendency to crack.</i> —None.
<i>Petiole size.</i> —Large.	45	<i>Blush color.</i> —Pl.55 L7 Near Rubient.
<i>Petiole length.</i> —4.53 to 5.12 inches [11.51 to 13.00 cm].		<i>Ground color.</i> —Pl.12 L1; Oil Y.
<i>Petiole color (lower surface).</i> —Pl.20 L8 Near Eden gr.		<i>Pulp.</i> —Near Pl.13 K3 Olive gr.
<i>Petiole color (upper surface).</i> —Pl.16 L8 Dark Cardinal.		<i>Lenticels.</i> —None.
<i>Petiole sinus form.</i> —Upside down 'U' shape.	50	Flesh:
<i>Lobe (average).</i> —Four.		<i>Flesh color.</i> —Pl.12 K3 Olive gr.
<i>Tooth number.</i> —Four to six.		<i>Juice production.</i> —Good.
<i>Tooth shape.</i> —Triangular.		<i>Flavor.</i> —Very good.
Inflorescence:		<i>Aroma.</i> —Mild.
<i>Size.</i> —6.70 to 7.50 inches [17.02 to 19.05 cm].		<i>Texture.</i> —Firm.
<i>Number per spur.</i> —Two to three.		<i>Ripening.</i> —Even.
<i>Number per vine.</i> —Many; up to sixty-four.	55	<i>Eating quality.</i> —Very good.
<i>Quantity.</i> —Proficient.		<i>Use.</i> —Fresh Market.
Flowers:		<i>Resistance to disease.</i> —Unknown.
<i>Flower buds.</i> —Small; 0.04 to 0.08 inches [1 to 2 mm].		<i>Harvesting.</i> —Late August in the San Joaquin Valley of Central California.
<i>Flower buds surface.</i> —Glabrous.		<i>Shipping and handling qualities.</i> —Good.
<i>Flower buds.</i> —Generally hoary.		Having thus described and illustrated our new variety of grapevine, I claim:
<i>Date of bloom.</i> —May 9, 2010.	60	1. A new variety of grapevine to be known as 'Sheegene-20' and parts thereof, substantially as illustrated and described, characterized principally by its production of medium to large, red-colored seedless grapes that mature later in the season of ripening than does 'Flame Seedless' (unpatented) that it resembles.
